Action Closing Prosecution (nonfinal), mailed by the USPTO on May 21, 2102 in case Control No. 95/001,854 filed Dec. 14, 2011.

(Continued)

Primary Examiner — Michael A Pratt(74) *Attorney, Agent, or Firm* — Covington & Burling LLP(57) **CLAIM**

The ornamental design for a broadhead, showing my new design.

DESCRIPTION

FIG. 1 is a three-quarter front view of the broadhead of the present invention in an inflight retracted position;
FIG. 2 is a side view of the broadhead of FIG. 1;
FIG. 3 is a top view of the broadhead of FIG. 1;
FIG. 4 is a front view of the broadhead of FIG. 1;
FIG. 5 is a rear view of the broadhead of FIG. 1;
FIG. 6 is a three-quarter front view of the broadhead of the present invention in an extended position;
FIG. 7 is a side view of the broadhead of FIG. 6;
FIG. 8 is a top view of the broadhead of FIG. 6;
FIG. 9 is a front view of the broadhead of FIG. 6; and,
FIG. 10 is an end view of the broadhead of FIG. 6.
